DEVICE FOR RAPIDLY MAKING CROSS SECTIONS OF FIBERS

John I. Hardy, Washington, D. C., dedicated to
the free use of the Public

Application December 14, 1932
Serial No. 647,190

2 Claims. (Cl. 88—40)

(Granted under the act of March 3, 1883, as
amended April 30, 1928; 370 O. G. 757)

This application is made under the act approved March 3, 1883, as amended by the act of April 30, 1928; and the invention herein described, if patented, may be manufactured and used by or for the Government for governmental purposes without the payment to me of any royalty thereon.

I hereby dedicate the invention herein described to the free use of the public, in the territory of the United States, to take effect upon the granting of a patent to me.

This invention relates to a device having a fiber hole and slot for use in rapidly making cross sections of wool and other fibers.

The rapid methods ordinarily used for making cross sections of fibers involve the use of a perforated metal disc or piece of cork.

In the case of the disc the fibers are threaded through a hole in the disc by a silk thread. When a piece of cork is used the fibers are also threaded through a small perforation by the use of a needle. The cross section of fibers is obtained by cutting the fibers close to the surfaces of the disc or cork by means of a sharp instrument. The disadvantages of these methods and devices are due to time consumed in passing the fibers through the disc or cork and to the fact that the individual fibers are doubled in the process. It is also found in drawing the fibers through a disc or piece of cork the tension exerted often breaks or distorts the shape of the fibers.

The objects of my present device are to more rapidly obtain good cross sections of fibers and at the same time eliminate the disadvantages of existing rapid methods as disclosed above.

I attain these objects by use of the device illustrated in the accompanying drawing in which Figure 1 is a top plan view of the entire device; Figure 2 is a plan view of the slide holder disc detached from its companion disc; Figure 3 is a top plan view of the fiber holder disc showing the fiber hole and slot; Figure 4 is a side view of the entire device; Figure 5 is a side view of the slide holder disc and Figure 6 is a detailed view of the metal slide.

The device involves use of a metal disc 1 called the fiber holder disc in approximately the center of which is a fiber hole 2 of a predetermined size. There is a fiber slot 3 in disc 1 extending from the hole 2 to the circumference of the disc. The second disc 4 called the slide holder disc which may or may not be the same size as the first mentioned disc also contains a slot 5 in which is rigidly affixed a flat surfaced metal slide 6 with right angled flanges 7, said slide extending sufficiently

beyond the slide holder disc to completely fill the above-mentioned slot 3 in disc 1.

That portion of the circumference of the slide holder disc which comes into contact with the circumference of the fiber holder disc adjacent slot 3 should be formed to the curvature of the circumference of the fiber holder disc. As an alternative the circumferences of the discs at the point of contact may be cut to form a straight line of contact between the edges of the discs.

The metal slide consists of a thin metal plate so formed as to have two flanges 7, 7 extending right angled to the central portion 10 of the plate in such a manner that when that portion of the plate which projects from disc 4 is inserted in slot 3 of disc 1 the aforementioned flanges will be positioned on opposite sides of disc 1 and the metal slide or plate will completely fill slot 3 thereby accurately completing the circumference of fiber hole 2 in disc 1. The flanges 7, 7 of the slide 6, as shown in Figures 2, 5 and 6 are discontinued a short distance from the free end of slide 6. This results in the edges of the central portion 10 of the slide 6, adjacent to fiber hole 2 being flush with the flat surfaces of the disc or plate 1, so that the fibers may be conveniently cut off flush with the sides of the fiber holder disc without dulling contact between the sharpened edge of the cutting tool and the slide.

If desired a locking device 8 may be utilized to hold the two discs together in order to prevent their separation by the pressure exerted by the compressed fibers. This locking device may consist, as illustrated, of two thin plates attached rigidly to one of the discs in such a manner that when the device is in an assembled position the plates will extend over the surface of the other disc. The free ends of the two plates are equipped with pins or knobs on the under surface thereof. This disc over which the plates extend contains perforations or indentations 9, 9 so positioned that when the above-mentioned extended portion of slide 6 is placed to its full depth in slot 3 the pins or knobs on the plates 10 will engage with such perforations or indentations.

To operate the device small groups of clean fibers are inserted into the fiber hole 2 through the fiber slot 3 until hole 2 is slightly more than full. Slide 6 is then inserted in slot 3 to its full depth and until the circumference of hole 2 is complete. By means of a safety razor blade the fibers are cut off flush on both sides of the fiber holder disc and are then ready for examination.

under the microscope. Should the fibers appear compacted too close this condition may be overcome by pulling out slide 6 a short distance. The device may also be used to assist in determining 5 the fineness of fibers.

Having fully disclosed my discovery I claim as my invention:

1. A device for use in making cross sections of fibers comprising a metal disc, a fiber hole in said disc, a slot extending from the fiber hole to 10 the edge of said disc, a metal slide so shaped that it may be inserted in said slot to a depth sufficient to close the circumference of the fiber hole and having flanges at right angles to said 15 slide which when adjusted embrace the top and bottom surfaces of the disc, a plate associated

with one end of said slide by which the slide may be conveniently handled and which is formed to align with the circumference of the disc and to serve as a gauge controlling the depth to which the slide may be inserted in said 80 slot.

2. A device for use in making cross sections of fibers comprising a plate, a fiber hole in said plate, a slot extending from the fiber hole to the edge of the plate and slide means in the slot to close the circumference of said fiber hole, 85 the edges of said slide means adjacent to the fiber hole being flush with the surfaces of the plate.
